UNITED STATES PATENT OFFICE.

JOHN DOYLE, OF NEW YORK, N. Y.

DESIGN FOR A GAS-LIGHTING FIXTURE.

41,682.

Specification for Design.

Patented Aug. 15, 1911.

Application filed April 19, 1911. Serial No. 622,173. Term of patent 14 years.

To all whom it may concern:

Be it known that I, JOHN DOYLE, a citizen of the United States, residing in the city, county, and State of New York, have invented a new, original, and ornamental Design for Gas-Lighting Fixtures, of which the following is a specification, reference being had to the accompanying drawing, forming a part hereof.

The figure is an elevation of my improved

ornamental gas lighting fixture, showing my new design.

I claim:

The ornamental design for a gas lighting fixture, substantially as shown.

JOHN DOYLE.

Witnesses:

GEORGE H. FORDMAN,
THOS. J. MELLOR.
